UNITED STATES PATENT OFFICE.

JOHN SIEWIOREK, OF GENEVA, OHIO.

BRICK CONVEYER.

1,407,173.

Specification of Letters Patent. Patented Feb. 21, 1922.

Application filed July 8, 1921. Serial No. 483,167.

To all whom it may concern:

Be it known that I, JOHN SIEWIOREK, a citizen of the United States, residing at Geneva, in the county of Ashtabula and State 5 of Ohio, have invented certain new and useful Improvements in Brick Conveyers, of which the following is a specification.

This invention has for one of its objects the provision of a conveyer for bricks, paving stones and like articles, from a source of supply to points along its length or conversely, to receive such articles and deliver the same at one end.

Another object is to provide means where- 15 by the conveyer may be moved transversely of its length as the work progresses.

A further purpose is to furnish means for adjusting the height of one end of the conveyer as may be necessary for its operation.

20 These several objects are attained by the novel construction and combination of parts hereinafter described and shown in the accompanying drawings, forming a material part of this disclosure, and in which:—

25 Figure 1 is a side elevational view of a conveyer made in accordance with the invention.

Figure 2 is a plan view of the same.

Figure 3 is an end elevational view looking from the raised end.

Figure 4 is a plan view of a modified type of conveyer roller.

Figure 5 is a perspective view of the conveyer fully assembled and shown in opera- 35 tion.

In the drawings the numeral 10 is used to designate in general a paved roadway having curbs 11 and 12 at its respective sides, beyond which a pavement 13 is indicated, 40 the paving material being represented by the bricks or stones 14 individually.

The conveyer is adapted to travel over the paved surface, moving the bricks into position convenient of access at any point 45 in the width of the road, as best shown in Figure 5.

Specifically the conveyer is comprised of a frame having a pair of spaced beams 15 rigidly connected and supported upon rollers 50 16 arranged to rotate freely between their ends on spindles 17, these rollers being so proportioned that their wide peripheries extend below the edges of the beams as shown, constituting a truck.

55 A pair of spaced uprights 18 are rigidly secured between the beams 15, extending in

parallel to a considerable height thereabove and have longitudinal grooves 19 in their inner adjacent surfaces.

A shaft 20 is journaled in the uprights, 60 near their upper ends, the shaft extending outwardly at one end and secured to it is a ratchet wheel 21, having a fixed stud 22 set in its outer side, the stud being pivotally connected with an operating handle 23, so 65 that the same may be extended and used as a crank for rotating the shaft.

Pivoted on the adjacent upright is a pawl 24, engageable with the teeth of the ratchet wheel 21, maintaining it from movement in 70 one direction.

A pair of cables 25 are fixed at one of their ends to the shaft 20 and can be wound thereon as the shaft is turned, the other ends of the cables being engaged with a cross bar 75 26 extending between the uprights and guided by the grooves 19 therein.

A pair of beams, arranged in two sections 28 and 29, are rigidly secured at their abutting ends by plates 30 and 31, through which 80 are passed bolts 32 forming firm, unyielding joints, this construction permitting the interchange of beams so that different aggregate lengths can be obtained.

The outer elements 29 have bolted to their 85 upper surfaces, a yoke 33 made of flat strip metal, bent to form a support 34 for a stud 35 on which is revolvably mounted a wheel 36 having a flange 37, the face of the wheel being slightly conical as shown.

Journalled at uniformly spaced intervals in the adjacent sides of the beams 28 and 29 are spindles 39 carrying rollers 40, these 90 rollers being cylindrical as indicated in Figures 2 and 5 or with recessed faces 41 as 95 shown in the detailed view Figure 4.

In operation, the proper length of beams 28 and 29 having been fastened together, the wheel 36 is disposed on one of the curbs, as 11, and the opposite ends of the beams rested 100 on the bar 26, the truck being placed closely adjacent the opposite curb 12.

By rotating the shaft 20, the bar and end of the conveyer beams will obviously be raised to any desirable height so that bricks, 105 from a pile as shown, may when placed on the free turning rollers 40, be moved by gravity down the inclined surface presented and taken off at any desired point as indicated.

It will be apparent that as the roadway is paved, the entire structure may be pushed

along over the finished surface so that a continuous supply of brick is delivered contiguous to the point where required.

It will also be evident that in removing 5 the bricks from a road-way, the same structure may be used, the bricks being delivered at the lower end of the conveyer.

Having thus described my invention, what 10 I claim as new and desire to secure by Letters Patent, is:—

1. A conveyer comprising a pair of spaced sectional beams, means for uniting the sections thereof, a plurality of freely revoluble rollers journaled between said beams, a 15 conically faced support wheel mounted at one end of said beams, said wheel having a flange on the side adjacent the rollers, means

for positively raising and lowering the other end of the beams, and means for retaining the beams in adjustment. 20

2. A gravity operated conveyer comprising a pair of beams adjustable in length to suit the width of a street, a truck mounted on rollers, said truck having grooved uprights, a windlass mounted in said uprights, 25 a bar movable in the grooves therein by said windlass, said bars supporting one end of said beams, a yoke connecting the opposite ends of said beams, a conical flanged wheel revolvably mounted on said yoke, and a plurality of closely spaced rollers freely rotatable between said beams. 30

In witness whereof I affix my signature.

JOHN SIEWIOREK.
